H. M. CONNOR AND D. D. MILES.
CARBURETER.
APPLICATION FILED JULY 23, 1917.

1,313,521.

Patented Aug. 19, 1919.

UNITED STATES PATENT OFFICE.

HERSCHEL M. CONNOR AND DON D. MILES, OF SAN FRANCISCO, CALIFORNIA, ASSIGNORS OF ONE-HALF TO ALBERT H. HERBERT, ONE-FOURTH TO MYRTLE C. MILES, AND ONE-FOURTH TO PANSY I. CONNOR, ALL OF SAN FRANCISCO, CALIFORNIA.

CARBURETER.

1,313,521.

Specification of Letters Patent. Patented Aug. 19, 1919.

Application filed July 23, 1917. Serial No. 182,342.

To all whom it may concern:

Be it known that we, HERSCHEL M. CONNOR and DON D. MILES, both citizens of the United States, residing at San Francisco, in the county of San Francisco and State of California, have invented certain new and useful Improvements in Carbureters for Internal-Combustion Engines; and we do hereby declare the following to be a full, clear, 10 and exact description of the invention, such as will enable others skilled in the art to which it appertains to make and use the same.

This invention relates to carbureters for internal combustion engines, but especially adapted for automobile engines, and has for its object to provide for the more efficient mixing of the fuel and air; to provide a means for the easy starting of the motor; 15 to avoid the employment of spring controlled valves, auxiliary air passages or moving parts other than the needle valve controlling the fuel level; and to provide a multiplicity of fuel jets by which the charge of fuel is 20 split up or divided into several parts that will facilitate the atomizing action.

With these and other objects in view the invention consists in the novel details of construction and combinations of parts 25 more fully hereinafter disclosed and particularly pointed out in the claims.

Referring to the accompanying drawings forming a part of this specification in which like numerals designate like parts in all the 30 views:—

Figure 1 is a sectional view of a carbureter made in accordance with this invention;

Fig. 2 is a side elevational view partly in section of the parts shown in Fig. 1;

Fig. 3 is a sectional view taken on the line 3—3 of Fig. 1 looking in the direction of the arrows.

1 indicates the upper portion of the outer shell of the carbureter, 2 the lower portion 45 of said shell, joined as at 3 to the upper portion 1, and provided with the hot air tube or passage 4 leading from the exhaust manifold in order that air drawn in by the carbureter will be preheated. 5 indicates a choke or 50 butterfly valve controlling the passage 4 and the admission of air into the chamber 6. Located inside the carbureter body portions 1 and 2 is the interior shell 7 provided with the helically disposed flanges or members 8

and to the lower end of said member 7 is 55 screw threaded the member 9, provided with the flange 10 against which fits the lower portion 2 of the carbureter proper as shown. Said member 9 is provided with the extension or member 11 surrounded by the member 12, provided with the coupling 13 leading from which is the fuel connection 14. Said member 12 is locked to said member 11 or held in place by the screw member 12'. The said connection 14 joins the passage 15 65 of the member 12 leading into the annular chamber 16, surrounded by the screen 17, and from said chamber lead the ports 18 into the chamber 19, from which leads the port 20 into the chamber 21; and 22 indicates 70 ports connecting said chamber 21 with the oil or fuel space 23 in which is located the float 24. A valve 25 controls the port 20 and is provided with a stem or extension 26 to which is secured the grooved member 27 75 adapted to be actuated by the ends 28 of the controlling weights 29 pivoted as at 30 to the bracket or support 31 carried by the sleeve 32, mounted on the support 33 as shown.

The lower end of the inner member or casting 7 is provided with a plurality of ports or passages 35 connecting the fuel space 23 with the annular chamber or main fuel supply 36, and 37 represents a port connecting said annular chamber 36 with a second annular chamber or auxiliary fuel supply 38 open to the atmosphere by means of the curved pipe 39. Passing through the upper wall 44 of the annular chamber 38 are the nozzles 40 and 41 having respectively the 90 fuel passages 42 and 43. The nozzle 40 is shorter than the nozzle 41 for a purpose that will appear below. Passing through the said upper wall 44 of the annular chamber 38 as well as through the upper wall 45 of the annular chamber 36 are the fuel nozzles 47 and 48 provided respectively with the bores or passages 49 and 50. 51 and 52 represent respectively a pair of additional fuel nozzles in all respects similar to the nozzles 47 and 48 and which likewise pass down through the said walls 44 and 45 into the annular main fuel supply chamber 36. It will be observed that both the nozzles 40 and 41 lead from the chamber 38 while the main 105 nozzles 47, 48, 51 and 52 lead from the main fuel supply 36.

It will be observed that the nozzles 40,

41, 47, 48, 51 and 52 are located in a circle and that they extend upwardly and into the annular passage 55 between the outer carburetor wall 1 and the inner member 7, so 5 that air which may be sucked through the passage 4 and from the chamber 6, will pass around said nozzles, and owing to a restriction in said passage to be described below, it will suck any fuel which may be 10 contained therein out of the respective bores, such as 42, 43, 49, 50, etc., so that said air will serve to finely subdivide or atomize the fuel found in said nozzles. The helically disposed members 8 carried by the 15 inner cylindrical member 7 form helical passages and it is preferred to so arrange the parts that there shall be a separate helical passage for each of the said nozzles. That is to say, the nozzle 47 for example, may 20 open or lead into a passage 56 while the nozzle 48 may lead into a companion helically arranged passage 57, etc.

It thus results that as the air drawn from the passage 4 circulates around the annular passage 55, in which the ends of said nozzles are located, the said air is separated or divided into parts, one of which traverses each of said helical passages such as 56 and 57, and thus there are as many separate 25 portions of the air as there are passages. By thus dividing the air into separate divisions or parts the atomization of the oil from each nozzle is greatly facilitated.

30 In order to more effectually suck the fuel out of the bores such as 42, 43, 49, 50, etc., of the nozzles I restrict the passage of the air from the annular chamber 55 into the respective helical passages such as 56 and 57, 35 by providing the solid portions 70 at the bottom of the helices, see Fig. 2, and in order to cause the fuel to more perfectly mix with the air the surfaces of the said solid portions 70 are curved as is indicated 40 at 59. The curved surfaces thus provided have the effect of causing the air to swirl around in the passages 56, 57, etc., and thus to thoroughly mix with the fuel as said fuel and air is sucked along said passages 45 into the chamber 63 to be mentioned below.

50 60 represents a pipe or passage connecting the chamber 61 above the float 24 with the atmosphere. 62 represents a throttle or other valve controlling the passage of mixed fuel and air into the engine and 63 represents the chamber or space into which the mixed fuel and air is delivered from the helical passages.

The operation of this device will be clear 60 from the foregoing but may be briefly summarized as follows:—

65 There being a suction created past the valve 62, preheated air will be sucked in through the passage 4 into the chamber 6 and into the annular chamber or passage

55 around the exits of the various nozzles such as 40, 41, 47, 48, 51, 52, etc. The float 24 having been so adjusted that oil will rise to a predetermined level, say slightly above the lower ends of said nozzles 40 and 41, 70 said air will suck fuel out of the nozzles including the nozzle 40 and the fuel thus sucked out of said nozzles by the said air will strike against the curved surfaces 59 of each helical passage, be given a rotary 75 or swirling motion in its appropriate passage, and will be drawn along said passages while still rotating, so that by the time it reaches the chamber 63 it will be thoroughly atomized or mixed with said air. 80 The said oil or other fuel thus at first sucked from the said nozzles will be a comparatively rich mixture, and therefore, will be suitable for the easy starting of the motor. But, the curved pipe 39 is so proportioned as to extend above the level of the oil or other fuel maintained in the chamber 23, and therefore, air will soon enter the said chamber 38 and occupy the bore 42, of the nozzle 40, so that after the initial 85 suction or starting of the engine, the nozzle 40 will deliver either a very lean mixture of fuel or else substantially pure air. The said nozzle 41, on the other hand, has its lower end extended down near to the 90 bottom of the chamber 38 as is plainly shown in Fig. 1, and as its bore 43 is located quite close to the port 37, it can receive oil or other fuel notwithstanding the admission of air into the 95 chamber 38 through the pipe 39. However, if the engine speeds up owing to the restricted character of the port 37, and its inability to supply a greater quantity of oil than will feed one nozzle such as 41, 100 the mixed fuel and air that leaves the nozzle 41 will be always a lean mixture while 105 the engine is running.

In the meantime, the air drawn through the passage 4 and from the chamber 6 into 110 and through the annular chamber 55 will continue to suck fuel from the main feed nozzles such as 47, 48, 51 and 52, and thus supply the engine. The ports 35 are made of sufficient dimensions to keep the annular 115 or main feed chamber 36 well supplied with fuel, and therefore, the nozzles such as 47, 48, 51 and 52 are always furnished with sufficient oil for the running of the engine.

The annular chamber 55 not only 120 envelops the nozzles 40, 41, 47, 48, 51 and 52, but it extends downwardly as shown, and surrounds the fuel chambers 36, 38 with the result that hot air from the chamber 6 freely circulates around said fuel chambers thus 125 effectually preheating the fuel sucked from said nozzles, and thereby greatly facilitating the atomization of said fuel and its subsequent mixture with said air.

It will thus be seen that as the engine 130

speeds up, fuel will cease to pass through the bore 42 of the nozzle 40 and a very small quantity of fuel will pass through the bore 43 of the nozzle 41, but larger and larger quantities of fuel will pass through the main feed nozzles such as 47, 48, 51 and 52. In other words, the auxiliary feed chamber 38 being open to the atmosphere, an increase in suction will have no effect upon the amount of fuel passing through the nozzle 41. An increase in suction on the other hand, will cause greater and greater quantities of fuel to pass through the main feed nozzles. Stated in other language, it will thus be seen that this carbureter employs no spring controlled valves and other accessories that are liable to get out of order, while it provides a means of furnishing a rich mixture for starting the engine, it furnishes a means of supplying a constant quantity of mixed fuel and air at low speeds through the nozzle 41 which is independent of the suction, and it furnishes a supply for said main feed nozzles 47, 48, 51 and 52, which supply varying quantities of fuel according to the speed of the engine.

So perfect is the atomization of the fuel that this carbureter is not only adapted for the ordinary gasoline fuels but it is also adapted for the heavier distillates such as kerosene. It will be observed that the parts may be readily assembled and disassembled, for repairs, cleaning, etc., in that it is only necessary to remove the locking bolt or screw threaded member 12' whereupon the fuel supply is readily taken off; and upon unscrewing the member 9, the lower port 2 of the carbureter readily separates from the upper port 1, and the port 7 may be readily withdrawn from said port 1.

As the float 24 ascends it contacts with the weights 29 which serve through their ends 28 to depress the needle valve 25 and thus cut off the supply of fuel. 75 represents the usual throttle controlling lever and 76 the usual pivot or shaft for the butterfly valve 5.

It is obvious that those skilled in the art may vary the details of the construction as well as the arrangement of parts without departing from the spirit of the invention, and therefore, we do not wish to be limited to the above disclosure except as may be required by the claims.

What we claim is:

1. In a carbureter the combination of a fuel supply; automatic means for controlling the flow of fuel to said supply; an intake through which air may be sucked; a plurality of nozzles located in the path of the sucked air; helically disposed means affording a plurality of independent paths for said air after leaving said nozzles; and means to restrict said paths around said nozzles, substantially as described.
2. In a carbureter the combination of a plurality of fuel supply nozzles; helically disposed means affording a passage of air around said nozzles; means to restrict said passages around said nozzles, said helically disposed means adapted to cause said air to assume a whirling motion after it passes said nozzles; and affording a plurality of independent passages for the mixed air and fuel as it leaves said nozzles, substantially as described.
3. In a carbureter the combination of a plurality of fuel supply nozzles; means to provide a helically disposed passage for each nozzle; means to cause air to flow past said nozzles into said passages; and means associated with said passages to restrict said air to cause it to assume a whirling motion as it leaves said nozzles, substantially as described.
4. In a carbureter the combination of a main fuel supply; a plurality of main fuel feed nozzles fed from said supply; an auxiliary fuel supply; means for admitting air to said auxiliary supply; a pair of nozzles one of which communicates with said auxiliary supply at its top and the other of which communicates with said auxiliary supply at a lower level; and means to conduct air past said nozzles, substantially as described.
5. In a carbureter the combination of a main fuel supply; a plurality of main fuel feed nozzles fed from said supply; an auxiliary fuel supply; means admitting air to said auxiliary supply; a pair of feed nozzles communicating with said auxiliary supply; a plurality of restricted helically disposed passages associated with said nozzles; and means to conduct air past said nozzles into said passages, substantially as described.
6. In a carbureter the combination of a plurality of main feed nozzles; means to supply fuel to said nozzles; a plurality of auxiliary nozzles; means to supply fuel to said auxiliary nozzles; means to admit air to said last named means; a helically arranged passage for each nozzle; means to conduct air past said nozzles into said passages; and means associated with said passages for imparting a whirling motion to the mixed air and fuel as it enters said passages, substantially as described.
7. In a carbureter the combination of a plurality of main feed nozzles; means to supply fuel to said nozzles; a plurality of auxiliary nozzles; means to supply fuel to said auxiliary nozzles; means to admit air to said last named means; a helically arranged passage for each nozzle; means to conduct air past said nozzles into said passages; means to automatically regulate the amount of fuel entering the carbureter; and means associated with said passages com-

prising a curved surface for imparting a whirling motion to the mixed air and fuel as it enters said passages, substantially as described.

- 5 8. In a carbureter the combination of a plurality of helically disposed open ended passages; means comprising a curved surface to restrict the passage of air and to impart a whirling motion to the same at one 10 end of each passage; a feed nozzle associated with each passage near said curved surface;

and means to conduct air past each nozzle and through each passage, substantially as described.

In testimony whereof we affix our signatures in presence of two witnesses.
